UNITED STATES PATENT OFFICE.

VAN BUREN ALLEN, OF BROOKLYN, NEW YORK, ASSIGNOR OF ONE-HALF TO WILL-GOTT KLINGBERG AND WESLEY EARL KLINGBERG, BOTH OF NEW YORK, N. Y.

PRISON LOCK.

Application filed February 8, 1921. Serial No. 442,030.

To all whom it may concern:

Be it known that I, VAN BUREN ALLEN, a citizen of the United States, residing at Brooklyn, in the county of Kings, State of New York, have made a certain new and useful Invention in Prison Locks, of which the following is a specification.

This invention relates to lock mechanism which is adapted to be applied to a door, or to each of a series, or tiers, of doors, gates and the like, and is so constructed and arranged that it may be operated by an attendant stationed at some distance from the door, or doors, to which the mechanism is applied, and which may be operated by a common operating lever or means.

The object of my invention includes the making of a lock mechanism which is strong, cheap and simple in construction, yet safe and effective in operation, and which is practically proof against tampering, or rendering inoperative by unauthorized persons.

It is my further object to provide a multiple of bolting or locking devices for each door or gate, and to so apply, locate and protect the same as to make it impossible to open said door when the same is locked. I have further provided a construction and means whereby said bolting and locking devices may be simultaneously operated either for locking or for unlocking said door, or tier of doors, or gates, or for leaving individual doors or gates in said tier locked.

I attain these objects by the mechanism illustrated in the accompanying drawing, in which—

Fig. 1 represents a plan view of a door or like construction having my invention applied thereto in locked position, but with the protective cover plates removed;

Fig. 2 represents a part of the same construction, as is shown in Fig. 1, but with the cover plates in place;

Fig. 3 shows the locking mechanism unlocked and unbolted;

Fig. 4 represents an end view of the locking mechanism taken on lines 4—4 of Fig. 3;

Fig. 5 shows the main lock bolt in locking position and ready to be unlocked by a key;

Fig. 6 shows the lock bolt in unlocked position; and

Fig. 7 represents a modification for operating the locking bolt simultaneously in either direction with the other locking mechanism, and without the use of a key.

Similar numerals refer to similar parts through out the several views.

Referring now to the drawings,—

8 represents a door or similar construction hingedly mounted at 9, and having my locking mechanism applied thereto, as is best shown in Fig. 1. This mechanism comprises a bolt 11, which is slidably held between guide lugs 12, 12', and a guide plate 13. The bolt 11 may be provided with a suitable indenture 14 for taking a key of any desired design or construction. Bolt 11 also carries a trigger finger 15, which is pivotally mounted on said bolt by a pin 16, having a head 17, and operating through a slide 18 in the guide plate 13. The trigger finger 15 is normally depressed by a spring 19 for the purpose hereinafter more fully explained.

Pivottally connected to the door, the lock-casing, or similar structure, at 20, is the bolt operating member A, having extension legs 21 and 22, an enlarged head 23 and an ear 24, the purpose and utility of which will be described below. A suitable spring 25 normally holds the bolt-operating member out of locking engagement as shown in Fig. 3 for example. A suitable casing 26, having a cover plate 27, is provided to protect this part of the lock mechanism.

A lock lever 28 is mounted on the door or other structure by a rivet 29. Connected to lever 28 is a plunger bar 30, having an expansion spring 30'. This plunger bar operates through a bearing 31 in the flange 32 to depress the bolt operating member A for the purpose stated below. An upper plunger arm 33 is also attached to lever 28. This arm extends through guide 34, and terminates in an enlarged head 35. Between the guide 34 and head 35 is a coiled spring 36, which co-acts with spring 30' to retract the lock lever when pressure on head 35 is relieved in the manner stated below.

An operating shoe 37 is pivotally mounted on the cell wall, or equivalent structure, by means of a pivot pin 38, and an extension 39 of shoe 37 engages an operating bar or lever 40 by means of a pivot pin 41 or equivalent structure. The operating bar is slidably held in lugs 42 and 43, and may extend along the entire cell corridor, or like structure, for operating a plurality of lock devices of the kind herein described. A second lock shoe 44 is mounted on the cell wall 45.

by a pivot pin 45, and is pivotally connected to the operating lever by a pin 46, or equivalent structure.

It will be observed that the shoes 37 and 44 are so constructed and mounted that when the operating lever is moved to the left, for example, the shoes will tilt forward, and toe 37 will depress the plunger bar 33 to operate the lock in the manner more fully described below. At the same time the foot of said shoe, and foot 47 of shoe 44 will be moved downward to thereby bolt the door or equivalent structure, as is clearly illustrated in Fig. 1. Lock lever 28 has an extension 48 for engaging lug 49, and leg 22, of the bolt operating member, is of sufficient length to catch under lug 50, when the lock lever is depressed in the manner stated above. Said lugs 50 and 49, respectively, form engaging positions or seats for the main and auxiliary bolts.

By moving the operating lever as stated above, shoes 37 and 44 will act as bolts for the upper part of the door against the upper edge of which they engage or are seated when in bolted position. Shoe 37 will at the same time depress the lock lever into lug engaging position at 49, and will also by depressing plunger 30 move the bolt operating member into operative position in the following manner. As the bolt operating member turns on pivot 20, the leg extension 22 moves into lug engaging position at 50, and head 23 moving on its pivot at 20, engages the pin head 17 to throw the main lock bolt into locking position. The head 23 serves also the important function of covering the key hole while in this position, as is clearly shown in Fig. 2. In this position, the door is bolted and secured at five different points, namely, at the upper part where the two shoes contact, at the side where lock lever 28 and leg 22 engage their respective lugs, and also where the main bolt 11 slides home. In this position the trigger finger positively locks the bolt against retraction by engaging with guide lug 12'. In unlocking this form of lock, it is necessary to employ a proper key for lifting the trigger finger which key then slides the bolt back. This can be done, however, only after the head of the bolt operating member has been moved back to unlocked position.

From the above description, it is apparent that when the bolt operating member is in locking position, the key hole is securely covered, thereby defeating any attempt to tamper with the lock while the door is locked. It is obvious also that the key hole is uncovered when the door is unlocked or when it is open. It is further obvious that I could readily provide a simple slide 60 and operated by a cam 61 to pro-

tect the key hole also while the door is open, if desired, as is diagrammatically illustrated in Fig. 2.

In Fig. 7 I have shown a modification of my bolt operating member which will obviate the use of a key for throwing the main bolt. Here the bolt operating member is operatively connected to the main bolt 11 by a suitable connection which is diagrammatically illustrated at 52 for sliding the bolt back and forth and the trigger finger may in this type of lock be omitted, if desired.

From the above description, it is apparent a tier or doors in any desired number may be locked or unlocked from a point remote from the doors by the simple movement of the operating lever, which obviously may be of any desired length necessary to operate all the door locks in a particular tier. It is obvious that by my invention all of the doors may be simultaneously locked, and the several auxiliary bolts may be simultaneously unlocked, but the main bolt may be left in a locked position, to be thereafter unlocked by a key or equivalent device. This may be desirable under certain conditions, but ordinarily all the doors will be locked and unlocked simultaneously by an attendant moving the operating lever.

While I have shown and described specific construction illustrative of my invention, I do not thereby desire to be understood as having thus limited myself, as obviously various modifications coming within the scope and spirit of my invention will suggest themselves to those versed in the art. What I claim, therefore, as new and useful and of my own invention and desire to have protected by Letters Patent is:

1. In a lock mechanism, a main bolt and auxiliary bolts, lock engaging seats for said bolts, means for simultaneously moving said auxiliary bolts into or out of said seats, and means associated with one of said auxiliary bolts for operating said main bolt.

2. In a lock mechanism, a main bolt and auxiliary bolts, lock engaging seats for said bolts, and means comprising a slidable bar for operating all of said bolts simultaneously.

3. In a lock mechanism, a main bolt and auxiliary bolts, lock engaging seats for said bolts, means for simultaneously moving said auxiliary bolts into or out of said seat, and an extension of one of said auxiliary bolts whereby said main bolt is moved.

4. In a lock mechanism, a main bolt and auxiliary bolts, lock engaging seats for said bolts, means for simultaneously moving said auxiliary bolts into or out of said seats, and an extension on one of said auxiliary bolts for moving said main bolt into locking position, and for protecting the same.

5. In a lock mechanism, a main bolt and

- auxiliary bolts, lock engaging seats for said bolts, means for moving said auxiliary bolts into and out of said seats, means carried by one of said auxiliary bolts for operating said main bolt, and means on said main bolt for locking the same against unlatching movement.
6. In a lock mechanism, a main bolt and auxiliary bolts, lock engaging positions for said bolts, and means comprising a slideable bar for operating all of said bolts in unison from a point remote from said locking mechanism.
7. In a lock mechanism comprising a lock having a key hole, a main bolt and auxiliary bolts, lock engaging seats for said bolts, means for simultaneously moving said auxiliary bolts into or out of said seats, and an extension on one of said auxiliary bolts for moving said main bolt into locking position, and for protecting said key hole.
8. In a locking system, a door, an operating bar or lever independent of said door, lock bolts on said lever functioning to lock said door, and additional locking means to further secure said door.
9. In a locking system, a door, lock bolts on said door, an operating bar and additional lock bolts adjacent said door, but independent thereof, said additional bolts being pivotally connected to said bar to lock said door and to operate the bolts on said door.
10. In a locking system, a door, lock bolts on said door, an operating bar adjacent said door, bolts independent of said door, but operatively connected to said operating bar for locking said door, and for controlling the locking action of the bolts on said door.
11. In a locking system, a door, main and auxiliary bolts on said door, other bolts adjacent said door but independent thereof, a bar or lever for operating said adjacent bolts, one of said bolts being in operative relation to said auxiliary bolts for causing the same to move into and out of locking position, and means on one of said auxiliary bolts to operate the main bolt.

In testimony whereof I have hereunto set my hand on this 19th day of January A. D., 1921.

VAN BUREN ALLEN.
